UNITED STATES PATENT OFFICE.

SAMUEL S. MORTON, OF UPPER SANDUSKY, OHIO, ASSIGNOR TO THE OHIO MANUFACTURING COMPANY, OF UPPER SANDUSKY, OHIO, A CORPORATION OF OHIO.

COOLER FOR EXPLOSIVE-ENGINES.

No. 839,617.

Specification of Letters Patent.

Patented Dec. 25, 1906.

Application filed October 26, 1905. Serial No. 284,273.

To all whom it may concern:

Be it known that I, SAMUEL S. MORTON, a citizen of the United States, residing at Upper Sandusky, in the county of Wyandot and State of Ohio, have invented certain new and useful Improvements in Coolers for Explosive-Engines, of which the following is a specification, reference being had therein to the accompanying drawings.

- 10 This invention relates to coolers for explosive-engines, being designed more particularly for use in connection with gasolene traction-engines for the purpose of cooling the water employed for keeping down the 15 temperature of the engine-cylinder, so that the same water thus cooled may be used over again for that purpose. The invention is, however, applicable to explosive-engines employed in other connections.
- 20 The primary object of the invention is to provide a simple and inexpensive cooling device of high efficiency which will require the use of only a small quantity of water, which will prevent the entrance of foreign materials into the circulation while exposing the water directly to contact with the air, and which may be readily carried upon the framework of a traction-engine of the class described.
- 25 To these ends my invention consists in certain novel features which I will now proceed to describe and will then particularly point out in the claims.

In the accompanying drawings, Figure 1 35 is a side elevation of a gasolene traction-engine having my improved cooler applied thereto. Fig. 2 is a perspective view of the cooler detached. Fig. 3 is a vertical sectional view taken transversely through the 40 cooler at a point slightly to the rear of the center thereof, and Fig. 4 is a detail view of one of the supports detached.

In the accompanying drawings I have 45 shown my invention as applied to a gasolene traction-engine of a known type as illustrating one embodiment of my invention, and in this type of engine the frame is composed of two parallel members 1, preferably in the form of channel-bars, as shown more particularly in Fig. 3, and the cooler comprises a 50 tank or reservoir 2, arranged to fit between the said longitudinal frame members at the front part of the machine, said reservoir be-

ing preferably provided along the top of its side margins with angle-irons 3, which rest 55 upon the tops of the members 1 and support the tank or reservoir in position. Said tank or reservoir may be secured in position in any desired manner.

From two opposite margins of the tank or reservoir, preferably the front and rear margins, there arises a plurality of supports 4, arranged in corresponding pairs. In the present instance I have shown four of these supports, two at the front and two at the 65 rear of the tank. They are each preferably given the inverted-V shape shown, being composed of rods which converge upward and unite near their upper ends, one of these supports being shown in detail in Fig. 4 of 70 the drawings. They may be supported from the tank at their lower ends in any suitable manner; but I prefer to mount them upon cross-pieces 5, secured on top of the tank, said cross-pieces being preferably in the form 75 of angle-bars, the horizontal members of which serve to secure said cross-pieces to the tank by riveting or otherwise connecting them to the angle-bars 3, while the vertical members of said angle-bars serve for the attachment thereto of the lower ends of the supports 4. This may be effected by forming the lower end of each of the diverging members 6 of the support 4 into perforated 80 lugs 7, by means of which said members may 85 be readily riveted or otherwise secured to the cross-pieces 5.

Each member 4 is provided at its upper end with a cap 8, and the caps of the opposite pairs of supports receive and close the 90 ends of a distributing-pipe 9, which is thus carried by the supports 4. Each distributing-pipe is perforated as to its lower portion, as indicated at 10. Said distributing-pipes are connected by a transverse pipe 11 at 95 their central portions to a supply or inlet pipe 12, which brings the heated water from the engine. (Shown at 13 in Fig. 1.) The lower ends of the members 6, lying opposite each other on opposite sides of the tank, may 100 be connected, if desired, by rods 14.

The structure thus described, which is located above the tank 2, serves to support the cooling-surfaces, which are formed of canvas or other suitable fabric. Preferably a single 105 sheet of canvas is employed in connection

with each pair of supports and distributing-pipe. These sheets are indicated by the reference-numeral 15. The arrangement for their support which I prefer is that shown in which each sheet has its central portion extended around the corresponding distributing-pipe 9 and connected below the same by a line of stitching, as indicated at 16, said stitching connecting the two bodies of canvas which lie on opposite sides of the diverging members 6 of the supports 4. The two halves of the sheet of canvas which extend downward divergently from this point have their front and rear margins passed around the members 6 of the support and fastened by lines of stitching, as indicated at 17. Where the lower transverse rods 14 are employed, the lower margins of the canvas are passed around said rods and connected by lines of stitching, as indicated at 18.

The tank 2 is preferably constructed of metal and is without a top, it being provided with a top or cover 19, preferably of canvas, although any suitable fabric will serve the purpose, and said canvas top is provided with a central opening 20, which is closed by a screen 21, which screen may be constructed of any suitable material.

22 represents the outlet-pipe of the cooler, which is connected to a pump 23, from which a supply-pipe leads to the engine-cylinder, being connected with the water-jacket space surrounding the same.

It will be seen that the heated water entering the cooling apparatus through the inlet-pipe 12 will be conducted by the transverse pipe 11 to the distributing-pipes 9 and will be discharged from these latter pipes, through the apertures 10 thereof, upon the sheets of canvas 15. Since two of these latter are brought together immediately below each distributing-pipe, the water will be distributed evenly from each pipe over both of the sheets below it, and the entire body of heated water will be equally distributed over the several sheets of canvas and flowing down along the same will be thoroughly exposed to the cooling influence of the atmosphere, which is free to circulate between the sheets and over both surfaces of each of them, for it will be seen that the space between the two diverging portions of each sheet of canvas is open at both ends; and since the arrangement of the sheets is generally longitudinal with respect to the machine as a whole the circulation of air through these spaces is promoted, especially when the machine is in motion. The water after having thus been thoroughly exposed to the atmosphere falls upon the canvas cover of the tank and enters the tank either by passage directly through said cover or through the central opening 20 thereof and the screen 21 which protects said opening. In either case no dust, dirt, or other material apt to clog the circulation is

permitted to enter the tank, while at the same time I am enabled to obtain a maximum cooling effect by the direct exposure of the water to the atmosphere. It will be understood, of course, that the cooled water thus stored in the tank is returned to the water-jacket of the engine-cylinder through the medium of the pipe 22, the pump 23, and the usual connections, thus keeping up a constant circulation of the water.

I do not wish to be understood as limiting myself to the precise details of construction hereinbefore described, and shown in the accompanying drawings, as it is obvious that these details may be modified without departing from the principle of my invention.

Having thus fully described my invention, what I claim as new, and desire to secure by Letters Patent, is—

1. A cooler for explosive-engines comprising a tank, upwardly-converging supports mounted on said tank, a distributing-pipe carried by said supports, and downwardly-diverging sheets of fabric connected to said supports and meeting below said pipe, substantially as described.

2. A cooler for explosive-engines comprising a tank, supports of inverted-V shape arising from opposite sides of said tank, a distributing-pipe mounted on said supports, and a sheet of fabric passing around said pipe, having its margins connected to the diverging supports, and having the portions thereof lying on opposite sides of the pipe drawn together below said pipe, substantially as described.

3. A cooler for explosive-engines comprising a tank, a plurality of supports of inverted-V shape arising from opposite sides of said tank and arranged in opposite pairs, a distributing-pipe mounted on the upper ends of each pair of supports, and diverging sheets of fabric carried by the members of the supports, each diverging pair of sheets meeting below a distributing-pipe, substantially as described.

4. A cooler for explosive-engines comprising distributing-pipes, sheets of fabric extending downward from said pipes to conduct the water exposed to the atmosphere, a tank located below said sheets, and a fabric cover for said tank provided with a central opening having a strainer, substantially as described.

5. In a gasoline traction-engine, the combination, with a frame and a gasoline-engine mounted on said frame, of a cooler for the cooling water of said engine comprising a tank supported on said frame, upwardly-converging supports mounted on the front and rear of said tank, a distributing-pipe carried by said supports and extending longitudinally of said traction-engine, and diverging sheets of fabric carried by said distributing-pipe and extending between the same and

said tank, said sheets of fabric being drawn together beneath said distributing-pipes, substantially as described.

6. In combination with a gasolene traction-engine, a cooler for the cooling water thereof comprising a tank supported upon the frame of the vehicle, a plurality of supports of inverted-V shape mounted in opposite pairs upon the front and rear sides of said tank, longitudinally-extending distributing-pipes, each mounted on one pair of said supports, and downwardly-diverging

sheets of fabric carried by said supports and meeting in pairs under each pipe, said sheets extending in the direction of travel of the machine and the spaces between them being open at each end, substantially as described. 15

In testimony whereof I affix my signature in presence of two witnesses.

SAMUEL S. MORTON.
